UNITED STATES PATENT OFFICE.

RICHARD J. HOLZER, OF WHITE PLAINS, NEW YORK.

DOUBLE-SEAT FAUCET.

1,163,236.

Specification of Letters Patent.

Patented Dec. 7, 1915.

Application filed June 16, 1914. Serial No. 845,456.

To all whom it may concern:

Be it known that I, RICHARD J. HOLZER, citizen of the United States, residing at White Plains, in the county of Westchester and State of New York, have invented certain new and useful Improvements in Double-Seat Faucets, of which the following is a specification.

My invention relates to new and useful improvements in valves and valve seats, such as are provided for sink faucets, basin cocks, bath cocks, compound stop cocks, ball cocks, and the like.

The principal object of my invention is to provide in a faucet or cock a double-headed valve and a double valve seat, arranging the two valve heads and their respective seats in such manner that only one valve head is ordinarily in use, while the other valve head is adapted to be brought into operation when the valve seat of the primary valve head has become worn down to such an extent that leakage occurs.

Another object of my invention is to provide for the primary valve head an adjustable valve seat which may be vertically adjusted to compensate for considerable wear of both its seating surface and of the primary valve head.

A further and more general object of my invention is to construct the faucet valve and valve seats with such regard to proportion, number and arrangement of parts that they embody the desired features of simplicity, durability, and efficiency, and may be cheaply manufactured.

The above and other incidental objects of a similar nature, which will be hereinafter more specifically treated, are accomplished by such means as are illustrated in the accompanying drawing, described in the following specification, and then more particularly pointed out in the claims which are appended hereto and form a part of this application.

Referring now to the drawings, wherein there has been illustrated the preferred embodiment of this invention as it is reduced to practice, and throughout the several views of which similar reference numerals designate corresponding parts, Figure 1 is a longitudinal section taken medially through the preferred form of faucet embodying my double valve; Fig. 2 is a section on the line 2-2 of Fig. 1; and Fig. 3 is a detail perspective view of the compound valve head.

In the embodiment of my invention shown in the accompanying drawing, the faucet consists in the body portion A having a removable bonnet B, an integrally formed inlet tube C, and an outlet nozzle or spout D. The body portion A of the valve is, of course, formed with a valve chamber E which is cut-off from the inlet passage by an integral web 10. The web 10 is formed with a passage or opening 11 through which the water may pass from the inlet tube into the valve chamber E, and thence through the outlet nozzle D.

Two concentrically arranged, spaced, vertically extending annular flanges, indicated at 12 and 13, surround the opening 10. The member 13 is of considerably greater height than the flange 12, so that the secondary valve head may be seated separately from the primary valve head and at a higher point, as will be hereinafter more fully explained. The flange 12 is externally screw-threaded to receive a removable valve seat 14 which, as shown in Fig. 2 particularly, may be vertically adjusted to dispose its upper edge above the upper edge of the flange 12 to compensate for wear either of the primary valve seat or of the primary valve head, indicated at 15. It will be obvious that the upper edge of the removable valve seat 14 forms the surface with which the lower face of the primary valve head 15 may be engaged when it is desired to seal the passage between the inlet C and outlet D.

The valve consists essentially in a stem 16 which is threaded for adjustment within the interiorly disposed internally screw-threaded neck 17 formed integrally with the bonnet B. On the lower terminal of the stem 16 are formed the primary valve head 15 and secondary valve head 18. The primary valve head is of less diameter than the secondary valve head, and is arranged in parallel spaced relation thereto, as shown particularly in Fig. 2. It is apparent that the member 15 is of considerable less diameter than the annular flange 13 so that it may be arranged interiorly thereof for engagement with the primary valve seat 14. The outer edge of the upper portion of the member 13 is provided with a peripheral groove which receives a sealing gasket 19.

It will now be apparent that in ordinary use the primary valve head 15 will, by engagement with the primary valve seat 14, seal the passage 10 between the inlet C and

the outlet D. Should the primary valve seat and valve head become worn, however, to such an extent that leakage occurs, the user of the faucet may, without the employment 5 of any tools, quickly repair the faucet by merely threading the valve seat 14 to its lowermost point on the flange 12. When the primary valve seat has been thus disposed, the secondary valve head 18 may be 10 engaged with the sealing gasket 19 and upper edge of the secondary valve seat or flange 13, thus effectively cutting off communication between the inlet and outlet of the faucet. It need hardly be explained 15 that, when it is desired to adjust the valve seat 14, it is only necessary to remove the bonnet B and with it the valve stem 16.

Upon inspection of Fig. 2 particularly 20 of the drawings, it will be noted that my faucet valve is so constructed that the primary valve head may alone be seated and the secondary valve head may, at the same time, be arranged in open position. Also, the primary valve seat 14 may be threaded 25 down to its lowest point on the flange 12, so that the primary valve head 15 will be unseated while the secondary valve head 18 will be seated on the secondary valve seat. The primary and secondary valve heads 30 are also adapted to be simultaneously seated, this result being accomplished by properly adjusting the primary valve seat 14 upon the flange 12.

In reduction to practice, it has been 35 found that the form of this invention illustrated in the drawing, and referred to in the above description as the preferred embodiment, is the most efficient and practical; yet realizing that the conditions concurrent 40 with the adoption of this device will necessarily vary, it is desirable to emphasize the fact that various minor changes in details of construction, proportion and arrangement of parts may be resorted to, when required, without sacrificing any of the advantages of this invention, as defined in the appended claims.

Having thus described the invention, what is claimed as new is:—

50 1. In a valve of the character described, the combination with a pair of concentrically arranged annular valve seats, of a valve stem, and a pair of fixed valve heads carried thereby, one of said valve seats being 55 adjustable with respect to the other whereby the valve heads may be selectively seated.

2. The combination with a faucet having a valve chamber and an inlet and an outlet communicating therewith, of a valve including 60 a pair of concentrically arranged annular flanges surrounding the entrance of the inlet into the valve chamber, one of said flanges being screw-threaded, a valve seat having threaded engagement on said threaded flange whereby it may be adjusted with

respect to the other flange which constitutes the second fixed valve seat, and a pair of separate valve heads, the first of which is adapted to seat against the first-mentioned valve seat, and the second of which is adapted to 70 seat against the second-mentioned valve seat, the adjustably mounted valve seat being movable to permit either of said valve heads to be seated when the other valve head is unseated according to the adjust- 75 ment of the adjustable valve seat.

3. The combination with a faucet having a valve chamber and an inlet and outlet communicating therewith, of a pair of concentrically arranged valve seats surrounding the entrance of the inlet into the valve chamber, and an integral double headed valve, one of said valve seats being adjustable with respect to the other valve seat, whereby either of the valve heads may be 85 seated when the other valve head is unseated or both valve heads may be seated at the same time according to the adjustment of the adjustable valve seat.

4. In a valve of the character described, 90 the combination with a pair of concentrically arranged annular valve seats, of a valve stem, and a pair of fixed valve heads carried thereby, one of said valve seats being adjustable with respect to the other, 95 whereby the valve heads may be either selectively or simultaneously seated according to the adjustment of the adjustable valve seat.

5. In a device of the character described, 100 the combination with a pair of rigidly mounted valve heads, of an annular up-standing flange providing a valve seat, a second upstanding flange surrounding said first mentioned flange in spaced relation 105 thereto, said second mentioned flange being connected to said first mentioned flange upon one side of and below said valve seat and providing a valve seat at its free end, one of said valve heads being adapted to engage 110 said first mentioned valve seat and being movable within said last mentioned flange and the other of said valve heads being adapted to engage the second mentioned valve seat.

6. In a device of the character described, the combination with a pair of rigidly mounted valve heads, of an annular up-standing flange, a valve seat adjustable vertically upon said flange, a second upstanding annular flange surrounding said first mentioned flange in spaced relation thereto and providing a valve seat at its free end, said second mentioned flange being connected to said first mentioned flange upon one 120 side of and below said first mentioned valve seat to define a chamber closed at one end and surrounding said first mentioned valve seat, one of said valve heads being adapted for movement within said chamber to en- 125 130

gage said first mentioned valve seat and the other of said valve heads being adapted to engage the second mentioned valve seat and coöperating with said last mentioned flange 5 to inclose said first mentioned valve seat and valve head within the chamber.

In testimony whereof I affix my signature in presence of two witnesses.
